UNITED STATES PATENT OFFICE.

ALBERT C. FOULK, OF DAYTON, OHIO.

RADIATOR CONDENSER FOR INTERNAL-COMBUSTION ENGINES.

Application filed November 11, 1922. Serial No. 600,275.

To all whom it may concern:

Be it known that I, ALBERT C. FOULK, a citizen of the United States, residing at Dayton, in the county of Montgomery and 5 State of Ohio, have invented certain new and useful Improvements in Radiator Condensers for Internal-Combustion Engines, of which the following is a specification.

This invention relates in general to a cooling system for motor vehicles and more particularly to a radiator for such a cooling system which is so designed that the loss of cooling fluid by evaporation therefrom is eliminated.

15 Considerable difficulty has been experienced in cooling all motors for motor vehicles, due to the fact that the motor operates most efficiently at a temperature which is in excess of that of the boiling point of 20 the cooling fluid employed. For this reason there is a considerable loss of cooling fluid, due to evaporation. Particularly is this true when the cooling medium is diluted with alcohol and other similar anti-freeze 25 solutions.

It is an object of my invention to provide a device in which the vapor from the main cooler of the cooling system passes therefrom to a condenser where it is reliquefied and its escape from the cooling system thereby prevented.

It is a further object of my invention to provide such a condenser as is readily adaptable to a radiator or prime cooler as 25 customarily used by motor vehicles.

Further objects of my invention will appear in the accompanying specification and claims and will be disclosed in the accompanying drawings in which,

40 Figure 1, is a front elevation of my device with a portion broken away.

Figure 2 is a side elevation of the device as shown in Figure 1.

Referring with greater particularity to 45 the drawings, 1 is the main radiator or prime cooler of my cooling system which is provided with a suitable inlet pipe, 3 an outlet, 2 for connecting the same to the motor in connection with which it is to be used. At 4 there is shown the usual filler cap which is secured to the filler tube 4^a. 5 is the usual overflow pipe and vent from my radiator system. At 6 there is shown the usual cooling tubes which may be of 50 any suitable standard construction.

At the upper portion of my prime cooler I have provided an upper header 7 and at the lower portion thereof a lower header 7^a, capable of holding a considerable quantity of the cooling medium.

In the upper portion of this header I have provided a condenser 8 of any conventional radiator construction, separated from the cooling medium in the header proper by a baffle wall 12, and connecting therewith through a series of ports 13, which ports as shown in Figure 1 are located at the lateral edges of the baffle plate. It will be further noted by reference to Figure 1 that the baffle plate is so designed that the 60 central portion is somewhat higher than the lateral portion adjacent to the ports for the purpose of draining the cooling medium from the condenser back through the ports 65 13 and into the header 7.

The filler cap hereinbefore discussed is attached to a tube 4^a which extends from the condenser and terminates at the baffle plate 12. The usual motor 14 is shown in 70 Figure 2 with a fan 10 connected to said 75 motor by any suitable connecting means 11. From the foregoing my device will be seen to operate as follows:

The cooling medium to be employed is supplied through the filler tube 4^a into the 80 header 7 until it reaches the level of the ports at the side of the baffle wall. The 85 filler cap is then tightened in the usual manner and the device is ready for operation. When the cooling fluid in the radiator 1 90 comes to the boiling point the vapors resulting from said temperatures will pass laterally through the ports 13 into the condenser 8 where they will be rapidly reliquefied and allowed to flow down the baffle 95 wall 12, thence through the ports 13 and into the header 7 where they are available for further cooling the motor.

Claims:

1. In a cooling system for internal combustion engines, a radiator assembly comprising a prime cooler, upper and lower headers for said prime cooler, and a condenser mounted above said upper header and separated therefrom by a baffle wall, 100 said baffle wall having laterally disposed ports for connection with said upper header.
2. In combination in a cooling system for internal combustion engines, a radiator assembly comprising a prime cooler, upper 105

and lower headers for said prime cooler, and a condenser mounted above said upper header and separated from the cooling medium therein by a baffle plate, laterally disposed ports in said baffle plate to permit the passage of the vapors from said cooling medium into said condenser, said baffle wall

sloping from the center downwardly toward its lateral edges to permit the drainage of the condensed cooling medium from the condenser into said upper header.

In testimony whereof I have affixed signature.

ALBERT C. FOULK.
